UNITED STATES PATENT OFFICE.

BARZILLAI C. MENDENHALL, OF FARMLAND, INDIANA.

FENDER FOR SEEDERS AND PLANTERS.

1,305,826.

Specification of Letters Patent. Patented June 3, 1919.

Application filed February 17, 1919. Serial No. 277,518.

To all whom it may concern:

Be it known that I, BARZILLAI C. MENDENHALL, a citizen of the United States, residing at Farmland, in the county of Randolph, and State of Indiana, have invented certain new and useful Improvements in Fenders for Seeders and Planters, of which the following is a specification.

The present invention comprehends generally improvements in that class of inventions known as seeders and more particularly relates to a fender for seeders and planters.

It is the primary aim and object of this invention to provide a device of the above mentioned character wherein the construction and arrangement of parts forms an improvement over the construction covered in my Patent No. 1,222,884 granted April 17th, 1917.

It is an additional and equally important object of this invention to provide a device of the above mentioned character wherein the body of the fender is of improved construction being designed at the forward end so as to prevent the stalks of corn from catching on it and being pulled out of the ground while the inner portions of the body of the fender are designed to form braces or supports to increase the rigidity thereof.

The invention also embraces the provision of a device of the above mentioned character wherein improved attaching means is employed and is designed with adjustment pieces to in consequence permit of the device being connected on various types of seeders and planters.

Among the other aims and objects of this invention may be recited the provision of a device of the above mentioned character with a view to compactness and wherein the number of parts are comparatively few, the construction simple, the cost of production low and the efficiency high.

Other objects, as well as the nature, characteristic features and scope of this invention will be more readily apparent from the following description taken in connection with the accompanying drawings and pointed out in the claims, forming a part of this specification.

In the drawings:

Figure 1 is a longitudinal sectional view showing the improved fender attached to a planter.

Fig. 2 is a perspective detail of the fender detached, and

Fig. 3 is a rear elevational detail looking toward the inside of the fender when detached.

Similar characters of reference are employed in all of the above described views, to indicate corresponding parts.

Referring now, more particularly, to the accompanying drawings there is illustrated a planter embodying generally a frame in the form of a beam 1 near the forward end of which is mounted a rotatable supporting wheel 2 while a seed box 3 is carried near the rear end of the beam 1. The drill 4 is arranged beneath the seed box while the usual disk 5 is carried by the drill frame. A pair of guide handles 6 extend rearwardly from the device. It is to be particularly understood that the specific construction of the planter forms no part of this invention being merely illustrated and described so that a clear understanding will be had of the fender generally designated by the numeral 7 which is detachably connected to the beam and the seed box so as to be positioned forwardly and to the sides of the planter for removing weeds or other obstacles from the path of the planter, being particularly designed for use when plaiting wheat in a corn field, the fender serving to brush aside the weeds and is so shaped that it will keep the corn stalks from catching thereon and being pulled out of the ground.

In reducing the present construction of shield to actual practice the same consists of a body 8 formed from a piece of sheet metal desirably bent to a substantially U-shaped configuration, the free edges of the body being rolled inwardly upon themselves to provide vertically arranged braces 9 which act to increase the rigidity of the body while in addition U-shaped bracing members 10 are employed and are secured as by suitable fasteners 11 to the inner surface of the body desirably in alignment with the upper and lower edges thereof.

In order to further increase the rigidity of the fender and facilitate the attaching of the same to the planter, a support or head piece 12 is employed and is secured to the inner surface of the intermediate portion of the fender and the bracing members and vertically thereof by a suitable fastener such as nut and bolt ar-

arrangements 13. The support is provided approximately medially of its ends with a vertical series of openings arranged in pairs while angle brackets 14 are employed and arranged in opposed relation with each other being engaged by the intermediate nut and bolt arrangement 13 which is adapted to be arranged through any of the openings in the medial portion of the support 12 for clamping or securing the angle brackets 14 in various positions of vertical adjustment. Subsequently, another nut and bolt arrangement 15 is passed through the laterally projecting portions of the angle brackets and through the outer end of the beam or tongue 1 for connecting the forward end of the fender body to the planter.

Other angle brackets 16 of a construction similar to the angle brackets 14 are adjustably connected to the upper projecting portion of the support or head piece and although they form no purpose in connection with the present construction of planter, they are designed to adapt the shield for connection with other types of planters.

In order that a draft device may be connected to the planter, a clevis 17 is adjustably mounted in the upper projecting portion of the support or head piece and is adapted to receive a draft device (not shown). For the purpose of detachably connecting the inner ends of the side portions of the body of the fender to the planter vertically disposed attaching bars 18 are employed and are secured as by suitable fasteners 19 to the inner surfaces of the lower bracing members 10 and positioned in opposed relation with each other, the medial portions being offset inwardly as at 20 while the upper attaching portions are provided with vertical series of openings 21 through which fastening devices 22 are adapted to be passed and also engaged with the planter for removably connecting the side portions of the body to the planter.

It is preferred that the lower bracing member 10 be right angular in cross section, that is, provided with a vertically disposed portion and a laterally disposed portion 23, these portions being designed to coact respectively with the inner face of the body and the lower edge thereof so as to increase the rigidity of the body.

It is believed in view of the foregoing de-

scription that a further detailed description of the invention is entirely unnecessary. Likewise, it is believed that the advantages of the invention will be readily apparent. However, it is to be particularly understood that the present construction of fender is adaptable for association with various types of seeders and planters as is apparent from the provision of the angle attaching brackets 14 and 16.

Still further embodiments of the invention than those herein especially defined may be resorted to as conditions or preference may dictate, as may be in keeping with the hereto appended claims.

Having thus fully described the invention, what is claimed as new and desired to be secured by Letters Patent, is:—

1. A fender of the character described including a body formed of sheet metal bent in a substantially U-shaped configuration, the rear edges being rolled inwardly to form braces for increasing the rigidity of the body, bracing members secured to the body at the upper and lower edges thereof, a supporting head piece secured to the forward end of the body, attaching brackets adjustably mounted on the head piece, and attaching arms carried by the inner surface of the side portions of the body near the rear ends thereof.

2. A fender of the character described including a substantially U-shaped body formed of sheet metal, the free edges of which are rolled upon themselves to provide vertically disposed braces, bracing members secured to the inner surface of the body near the upper and lower edges thereof, a supporting head piece secured vertically of the inner surface of the intermediate portion of the body and the bracing bars, attaching brackets adjustably connected vertically of the inner surface of the head piece, a clevis carried by the upper projecting portion of the head piece, attaching arms having their inner ends secured to the lower bracing members near the free ends thereof and arranged in opposed relation with each other and positioned vertically of the body and having the upper attaching portions provided with vertical series of openings, and fastening means engageable with any of the openings.

In testimony whereof, I affix my signature hereto.

BARZILLAI C. MENDENHALL.

Copies of this patent may be obtained for five cents each, by addressing the "Commissioner of Patents, Washington, D. C."
